UNITED STATES PATENT OFFICE.

WILLIAM H. GROW, OF WINFIELD, KANSAS.

ROOF.

SPECIFICATION forming part of Letters Patent No. 674,579, dated May 21, 1901.

Application filed September 4, 1900. Serial No. 28,997. (No model.)

To all whom it may concern:

Be it known that I, WILLIAM H. GROW, a citizen of the United States, residing at Winfield, in the county of Cowley and State of Kansas, have invented certain new and useful Improvements in Roofs; and I do hereby declare the following to be a full, clear, and exact description of the invention, such as will enable others skilled in the art to which it appertains to make and use the same.

This invention relates to roofs or coverings for houses and structures of every nature requiring a top closure to exclude rain, snow, sunshine, wind, dust, and the like.

15 The invention deals more particularly with the covering applied to the sheathing and with the seams between the strips of roofing, said seams being standing and the roof material being paper and textile.

20 For a full description of the invention and the merits thereof, and also to acquire a knowledge of the details of construction of the means for effecting the result, reference is to be had to the appended description and drawings hereto attached.

25 While the essential and characteristic features of the invention are necessarily susceptible of modification, still the preferred embodiment of the invention is illustrated in the accompanying drawings, in which—

30 Figure 1 is a perspective view of a portion of a roof embodying the invention. Fig. 2 is a cross-section. Fig. 3 is a detail view of the invention applied to the valley portion of a roof.

35 Corresponding and like parts are referred to in the following description and indicated in all the views of the drawings by the same reference characters.

40 The roof, of whatever structure or architecture, comprises rafters or the like and sheathing, to which the covering is applied.

45 The roofing or covering consists of strips 1 of tar-paper, felt, or like cheap covering and strips 2 of burlap or kindred textile. These strips 1 and 2 overlie each other, the textile being uppermost, and a layer 3 of hydraulic cement is interposed between the coverings, being dusted upon the paper 1 prior to plac-

50 ing the cloth 2 thereon. A coat 4 of tar-paint, asphalt, pitch, or the like is brushed over the burlap or textile 2 and permeates the

meshes thereof and the cement 3 and binds all together, besides rendering the outer textile covering waterproof. Sand 5 is applied 55 to the coat 4 before it dries or hardens, thereby adding materially to the durability of the roof and increasing its qualities to resist wear. The strips 1 and 2 are rolled or bolted and preferably are of like width. When 60 either strip is jointed in its length, the adjacent end portions of the parts are lapped about a foot, and care should be taken not to have the joints of the under and the upper strips register. The seams between the strips are 65 standing and are formed in the following manner: Ribs 6 are nailed or otherwise fastened to the sheathing and are spaced apart a distance to admit of the longitudinal edge portions of the strips extending up one side 70 and over the crest thereof. These ribs may be wood or metal (wood being preferred) and may have any cross-sectional outline. In the preferred form the ribs 6 are triangular. The longitudinal edge portions of adjacent strips 75 alternately overlap upon opposite sides of the ribs, as shown, and the seam is finished by placing thereover a narrow strip 7 of burlap or textile cemented thereto by pitch, tar, or paint. The paper covering 1 is secured at 80 intervals to the sheathing by daubs 8 of pitch, paint, or like material. This obviates puncturing the material of the roofing and provides a cheap and effective securing means to prevent wind from stripping the roofing 85 from the sheathing between the ribs.

When the roofing is required to be flashed, a right-angled strip 8^a is secured to the sheathing in the angle formed between the roof and the wall 9, and the edges of the covering- 90 strips 1 and 2 pass thereover and under the flashing 10.

The valley of the gable-roof has the covering-strips 1 and 2 fitted thereto, and the ends of the ribs adjacent to the valley overlap the 95 edge portions of the valley-covering and assist in holding it in place. The lower ends of the gable-strips overlap the edges of the valley-covering. The joints of the outer strips are strengthened by cementing pieces 100 of burlap or textile thereto.

It is to be understood that within the purview of the invention the number of courses of paper, textile, and cement may be extend-

ed to provide a covering of desired thickness and that the sides of the ribs may be coated with pitch or paint to cause the roof material to adhere thereto and prevent wind stripping the roofing from the ribs at the seams. The edges of the strips at the standing seams may be tacked to the ribs prior to placing the covering-strips in position. The dry hydraulic cement may be retained in steep places by pitch, paint, or the like applied to the surface to be protected. At the eaves the roof material will be bent down over the drip-board in the usual manner, and at the angles and seams the material will be cut to facilitate the bending thereof.

Having thus described the invention, what is claimed as new is—

In roofing, a lower covering, an upper covering, a pulverulent material between the coverings and a coating of paint or the like applied to the upper covering and binding it, the pulverulent material and the lower covering together, substantially as described.

In testimony whereof I affix my signature in presence of two witnesses.

WILLIAM H. GROW. [L. S.]
